(57) **CLAIM**

The ornamental design for a device for sensory enhancement or sensory conditioning as shown and described.

DESCRIPTION

FIG. 1 is front right top perspective view showing our new design.

FIG. 2 is a front elevation view thereof.

FIG. 3 is a back elevation view thereof.

FIG. 4 is a top plan view thereof.

FIG. 5 is a bottom plan view thereof.

FIG. 6 is a right side elevation view thereof.

FIG. 7 is a left side elevation view thereof.

FIG. 8 is a perspective view, thereof, and shown in an alternate configuration; and,

FIG. 9 is another perspective view, and shown in an environment.

In the drawings, the evenly spaced broken lines are for the purpose of illustrating portions of the device for sensory enhancement or sensory conditioning that form no part of the claimed design. In FIG. 9, the dash-dot broken lines are for the purpose of illustrating environment only, and form no part of the claimed design.
